UNITED STATES PATENT OFFICE.

WALTER T. FLING, OF SAVANNAH, MISSOURI.

OIL-BURNER.

1,306,955.

Specification of Letters Patent. Patented June 17, 1919.

Application filed November 29, 1918. Serial No. 264,630.

To all whom it may concern:

Be it known that I, WALTER T. FLING, a citizen of the United States, residing at Savannah, in the county of Andrew and State of Missouri, have invented certain new and useful Improvements in Oil-Burners; and I do hereby declare the following to be a full, clear, and exact description of the invention, such as will enable others skilled in the art to which it appertains to make and use the same.

This invention relates to hydrocarbon burners, and aims to provide a novel and improved burner for consuming kerosene or other distillates or oils.

It is the object of the invention to provide such a burner comprising a novel construction and assemblage of the component elements, whereby the burner is rendered practical, efficient and particularly useful in cook stoves, ranges and the like, although the burner can be modified for use in furnaces, water heaters, steam boilers and elsewhere.

A further object is the provision of a burner which can be manufactured at small cost and the parts readily assembled as well as being readily taken apart for purpose of cleaning, repairing or replacement, the main parts of the burner being readily cast from suitable metal.

A still further object is to provide novel means for generating the oil or liquid fuel into vapor in starting the burner and after the generator or retort has been primed, so that the vaporization is started effectively and continued.

With the foregoing and other objects in view, which will be apparent as the invention is better understood, the invention resides in the construction and combination of parts as hereinafter described and claimed, it being understood that changes can be made within the scope of what is claimed without departing from the spirit of the invention.

The invention is illustrated in the accompanying drawings, wherein:

Figure 1 is a plan view of the improved burner.

Fig. 2 is an end view.

Fig. 3 is a longitudinal vertical section taken on the line 3—3 of Fig. 1.

Fig. 4 is a cross section taken on the line 4—4 of Fig. 3.

In carrying out the invention, the body

1 of the burner is bowl-shaped, and elongated as shown, and is provided with a central depression or cavity 2 through one end wall of which is threaded or otherwise inserted a mixing tube 3 that projects into the depression 2 for delivering the mixture of vapor and air into said depression so as to rise within the body or bowl 1. An air entry casing 4 is threaded or otherwise engaged upon the outer end of the mixing tube 3, and has air inlet openings 5 controlled by a rotatable shutter or valve 6 to control the supply of air as desired.

A burner head or top 7 is disposed within the mouth or rim of the top 1, and is provided with a series of slots 8 therein, preferably disposed obliquely from side to side as clearly seen in Fig. 1. These slots are for the outlet of the mixture upwardly therethrough from within the body and distribute the flames over the area of the burner head or top 7 which is concentric within the body and similar in shape. The head or top 7 has its margin extended downwardly, outwardly, and upwardly to form a marginal trough 10 for holding a charge of priming fuel to start the burner. It is preferable to provide an asbestos wick 11 within the trough 10 for holding the fuel and facilitate the priming operation. The outer wall of the trough 10 fits snugly within and against the rim of the body or bowl 1, so as to support the head or top 7 which rises from within the surrounding trough. The burner head or top 7 is preferably provided with a longitudinal reinforcing rib 9 extending from one end to the other and depending from said head or top between the ends of the slots 8, and said slots extending into the rib 9, as seen in Figs. 3 and 4.

A shield 12 of the same form as the top of bowl 1 is seated on the rim thereof, the lower edge portion of the shield being offset outwardly, as at 13, so as to seat on the edge of the body and removably support the shield. The shield, as shown, curves inwardly so as to overhang the priming trough 10, and said shield is provided near its lower edge or immediately above the offset portion 13 with air inlet apertures 14, which admit air into the shield to pass over the trough 10 and to the slots 8. These apertures 14 are located at intervals throughout most of the periphery of the shield. This shield 12 as well as the body 1 and head or top 7 can be readily cast from suitable metal, although they can

be manufactured in other ways. Furthermore, said parts can be readily assembled and taken apart, the top and shield being both supported by the rim of the body.

5 A generator coil or retort 15, formed of suitable tubing, is disposed within the shield 12 above the priming trough 10 and surrounding the slotted portion of the burner head or top 7, so that this coil will surround 10 the flames above the slots 8 to be heated thereby after the burner is started and the coil in being disposed over the trough 10 will be quickly heated by the priming fuel which burns within said trough in starting 15 the burner. The shield 12 protects the coil or tubing 15 and also confines the flames so that they will not spread from the body or bowl 1, and said shield is also useful as a support for kettles or other objects to be 20 heated, inasmuch as they can be seated on the upper edge of the shield over the flames. In addition, the shield 12 also supports the generator or retort. Thus, a clip 16 embraces the coil 15 at one end of the shield, 25 and is secured to said end of the shield by a bolt 17 or other securing element, thereby supporting the coil at this point. The other end of the shield 12 has notches 18 in its upper edge through which the terminals of 30 the coil or tubing 15 project outwardly below the upper edge of the shield, and said terminals are seated in said notches to support the coil.

A fuel supply pipe 19 is connected to one 35 terminal of the coil 15, and has a valve 20 for controlling the flow of fuel into the coil or generator. The other terminal of the coil 15 is extended downwardly, as at 21, and has a jet or nozzle 22 slipped into the casing 40 4, the discharge of vapor from the nozzle 22 being controlled by a suitable valve 23. The vapor issuing from the nozzle 22 passes through the casing 4 into the mixing tube 3 45 and sucks in air through the openings 5 which will admix with the vapor, so that a proper mixture is forced into the body.

In starting the burner, a small quantity of priming fuel is poured in the trough 10 and will be absorbed by the asbestos wick 11 50 therein. Then, by lighting the priming fuel, the flames will rise and heat the coil 15 so that when the valve 20 is opened and fuel

admitted into the coil, the fuel will be vaporized and will discharge from the nozzle 22, thus supplying the mixture which is 55 forced up through the slots 8 to support the flames when the mixture issuing from said slots is ignited. The coil 15 in surrounding the field of flames will be kept hot so as to 60 continue the generation of vapor.

Having thus described the invention, what is claimed as new is:—

1. A burner embodying a bowl-shaped body, a top having vapor outlets and a marginal priming-fuel trough surrounding the 65 outlets and fitting within the rim of the body and a generator coil above said trough having an outlet communicating with the body to deliver vapor thereinto.

2. A burner embodying a bowl-shaped body, a top having a raised portion with vapor outlets, and a marginal priming-fuel trough surrounding said portion and fitted within the rim of the body, and a generating coil above said trough and having a delivery end communicating with the body to 75 deliver vapor thereinto.

3. A burner embodying a bowl-shaped body, a top having vapor outlets and a marginal priming-fuel trough surrounding said 80 outlets and fitting within the rim of the body, a shield supported over said rim, and a generating coil within the shield above said trough and having an outlet for delivering vapor into the body.

4. A burner embodying a bowl-shaped body, a mixing tube for delivering vapor into said body, a top having a raised portion with vapor outlets and a surrounding marginal priming-fuel trough fitting within the 90 rim of the body, a shield supported on the edge of said rim and overhanging said trough, and a generating coil supported by and within the shield over said trough and having an outlet nozzle to direct the vapor 95 into the mixing tube.

In testimony whereof I have signed my name to this specification in the presence of two subscribing witnesses.

WALTER T. FLING.
